UNITED STATES PATENT OFFICE.

CAROL LEWIS STRAUSS, OF MILLINOCKET, MAINE.

SAFETY PIN.

1,402,109.

Specification of Letters Patent. Patented Jan. 3, 1922.

Application filed January 14, 1921. Serial No. 437,270.

To all whom it may concern:

Be it known that I, CAROL LEWIS STRAUSS, a citizen of the United States, residing at Millinocket, in the county of Penobscot and State of Maine, have invented a new and useful Safety Pin, of which the following is a specification.

My invention relates to a safety pin to be used in connection with a brooch clasp to prevent the loss of the brooch in case of the slipping of the clasp and to hold the brooch in position.

Fig. 1 is a plan view of my invention and Fig. 2 an end view. Fig. 3 is a perspective view, with the clasp closed. Fig. 4 is a side view, showing the method of operation.

1 is the base of the brooch. 2 is a clasp pin which is attached to the base 1 by any suitable fastening. I here show the clasp pin, pivotally attached to a bearing 3 by a shaft 4. The clasp pin 2 has preferably an enlargement or stop 5 at its pivoted end which limits its downward movement, but is free to move upwardly, that is, away from the base. A catch 6 receives the free end of the pin 2 and holds it down against the spring pressure caused by the stop 5. This is all well known and any similar pin fastening may be used.

The novelty of my invention consists in combining with the clasp above described or any similar clasp, a safety pin 7 of substantial length attached to the base beside the catch 6 and running in the opposite direction from the clasp pin 2 along the base

of the brooch and approximately parallel with the clasp pin 2. It should be long enough to pierce the cloth twice.

I push the clasp pin 2 through the garment, preferably so that the cloth will bunch near the head of the clasp pin 2 and then draw the brooch to the right, thus inserting the pin 7 so that when the cloth is straightened out the cloth will be pierced twice by each pin, with both pins well buried in the garment. Any movement of the pin thereafter will only embed one of the pins deeper in the garment, whether the catch 6 is released or not and moreover, the brooch is held against turning.

50

I claim:

In a brooch or similar article; the combination of a clasp pin attached at one end to the body of the brooch, the pin extending beneath the body of the brooch and having its free end movable from and toward the brooch; a catch arranged to limit the movement of the movable end of said clasp pin from the brooch when engaged therewith and to permit disengagement of said pin 60 from the catch, and a safety pin attached to the brooch body beside the catch, directly beneath the body of the brooch, said safety pin running from its point of attachment approximately parallel to the base of the 65 brooch and extending toward the end of the brooch to which the clasp pin is attached.

In testimony whereof I affix my signature.

CAROL LEWIS STRAUSS.
